UNITED STATES PATENT OFFICE.

GEORGE D. MAYO, OF LACONIA, NEW HAMPSHIRE.

KNITTING-MACHINE.

1,107,816.

Specification of Letters Patent. Patented Aug. 18, 1914.

Application filed February 17, 1908. Serial No. 416,171.

To all whom it may concern:

Be it known that I, GEORGE D. MAYO, a citizen of the United States, and a resident of Laconia, in the county of Belknap and State of New Hampshire, have invented an Improvement in Knitting-Machines, of which the following description, in connection with the accompanying drawings, is a specification, like letters on the drawings representing like parts.

This invention in knitting machines relates more particularly to machines employed in the production of hosiery.

My invention may be conveniently illustrated in connection with the machine shown and described in Letters Patent of the United States issued to me, dated April 21, 1903, No. 726178, to which reference may be had.

My invention consists in certain improvements in the construction of a knitting machine, which will be hereinafter more particularly referred to.

In the accompanying drawings: Figure 1 illustrates in side view and partial section a knitting machine such as shown in my earlier patent referred to; and Fig. 2, a perspective detail to be described. Fig. 3 is a diagram of one product of the machine illustrating areas knit at different speeds.

The accompanying drawings, exhibiting an illustrative embodiment of my invention, show a sufficient portion of an operative knitting machine to enable my invention to be understood.

The needle cylinder 1 and its carrier 2 having a lug 3, resting upon a supporting rod 4 mounted in the base plate A and frame of the machine, the skeleton cylinder S, the needle cylinder support or carrier 2 vertically movable within a guide 6 depending from the bed plate of the machine head; the needles n, n mounted in the needle cylinder and having their butts n' working between the bars 8 of the skeleton cylinder, are and may be similar in construction and general mode of operation to the corresponding parts similarly designated, in my said Patent No. 726178. The bevel gear 39 forming part of the driving mechanism for said machine, and the clutch mechanism of which the lever 120 constitutes a part, may also be similar to that illustrated in my said patent. The thread changing, reinforcing, and picker operating mechanism of which the vertical operating rod 92

is herein shown, together with the segment gears 95, 96, the arm 98, operated by a cam in the barrel 101, the pattern chain 147 and parts controlled thereby, may likewise be similar in construction and operation to the correspondingly designated parts in my said patent. The horizontal barrel 101, provided with face cams 194, 195, which cooperate with adjustable contact members 199 on a lever 196, fulcrumed at 197 to act upon a lug 198 on said supporting rod 4 and lift the needle cylinder, operates as in my said patent to lengthen the stitches substantially simultaneously with the change from circular to reciprocatory knitting. This is because the slower motion of the cylinder together with the tension of the take-up on the yarn, during reciprocatory knitting, causes the stitches to be drawn more tightly and therefore to a shorter length than under the higher speed of circular work, without the take-up. I have found, however, that for the best results the speed of the circular knitting should be reduced substantially to that for reciprocatory knitting prior, by one or more courses, to the actual change to reciprocatory knitting, but the last one or more courses of circular work so knit under the reduced speed would, under usual conditions, exhibit a closer and shorter stitch than the circular work immediately preceding it, and also shorter than the work following it in the foot, as indicated in Fig. 3. In said figure, the leg L may have been knit at a normal speed as far as the line x, whereupon the remaining circular courses y exhibit the effects noted. Following the reciprocally knit heel H, made at the slower speed, the circular foot F may be knit at a normal speed, the reduction prior to the reciprocally knit toe T taking place at the line x', leaving the courses at y' to be knit at the reduced speed. To obviate this, I have herein provided said lever 197 (see Fig. 2) with an auxiliary arm 400, fulcrumed thereon at 401 and provided with a roller stud 402 that overlies the cams 194, 195. This auxiliary stud 402 is met by said cams sufficiently in advance of the time when said cams would act to lift the lever 196 and its needle cylinder, to cause said lever to be lifted to lengthen the stitches at the moment of reduction in speed, thereby offsetting the stitch shortening tendency due to the speed reduction and causing the circular courses thereafter knit by the slower

speed of the machine to appear of substantially the same length as those preceding and following it, knit at the higher speed and with the cylinder depressed.

5. The additional or thickening thread commonly thrown in for the heel, or the different thread used in knitting the heel, is provided for and taken into consideration in adjusting the contact members 199 on the lever 196, to raise the needle cylinder for lengthening the stitches during the reciprocatory movements of the machine. When, however, said needle cylinder is raised for lengthening the stitches during the last 10 complete rotations of the cam cylinder while the speed is reduced immediately preceding reciprocatory knitting, no additional or heel threads are in use—they are not brought into use until the reciprocatory knitting actually begins—and because of this and other 15 and varying conditions it is important that the means for raising the needle cylinder to lengthen the stitches prior to reciprocatory knitting be adjustable independently of the 20 stitch lengthening means that are employed during reciprocatory knitting. This is provided for in the construction described by employing a separate adjusting screw 403 for varying the adjustment of the auxiliary 25 arm 400 relative to its main arm 196. By means of this adjustment the needle cylinder may be raised in advance of reciprocatory knitting sufficiently to produce stitches which, under the slower rotations of the 30 cam cylinder and without any additional or heel thread, will appear to the eye as similar to those preceding them, knit at the highest rotative speed, and similar also to those following, knit at the slower reciprocatory 35 speed with the heel thread or threads in use.

I have found it unnecessary, commercially, to provide similar means to operate immediately following the reciprocatory knitting, as the conditions are such that while such 40 means, or equivalent means, might be employed if desired, practically I have found them to be unnecessary.

Claims

1. In a knitting machine adapted for circular and reciprocatory work, circular and reciprocatory knitting means, speed reducing means operative during circular knitting in advance of said reciprocatory knitting means, and means to lengthen the stitch 50 during circular knitting simultaneously with the reduction in speed and in advance of the reciprocatory knitting to an extent to compensate for the reduced stitch length incident to speed reduction.

60. 2. In a knitting machine of the class referred to the needle cylinder, supporting post therefor, a lever to lift said post and cylinder, one or more cams to act upon said lever, and auxiliary means on said lever to 65 cooperate with said cams and to advance the

action of said lever in lifting said cylinder.

3. The needle and skeleton cylinders, the rod 4, the co-acting lever 196 and cams cooperating therewith to operate it, the auxiliary arm 400 operatively connected to lever 196 and its roller, stud 401, combined and operating as described.

4. In a knitting machine adapted for circular and reciprocatory work, circular and reciprocatory knitting means, speed reducing means effective during circular and reciprocatory knitting, and means to lengthen the stitches to different lengths preceding and also for reciprocatory knitting to compensate for decreased stitch length incident to speed reduction.

5. In a knitting machine adapted for circular and reciprocatory work, means to operate the parts for circular knitting, means to operate the parts for reciprocatory knitting at less than the maximum speed for circular knitting, means to reduce the speed of the parts for one or more courses just prior to reciprocatory knitting, means to lengthen the stitches during and for reciprocatory knitting and co-operating connections to lengthen the stitches during and for the reduction in speed just prior to reciprocatory knitting, said connections being adjustable independently of said means to lengthen the stitches during reciprocatory knitting.

6. In a knitting machine adapted for circular and reciprocatory work, means to operate the parts for circular knitting, means to operate the parts for reciprocatory knitting at less than the maximum speed for circular knitting, thread thickening mechanism for reciprocatory knitting, means to reduce the speed of the parts for one or more courses just prior to reciprocatory knitting, means to lengthen the stitches during and for reciprocatory knitting substantially equal in length the normal stitches of circular knitting, and co-operating connections to lengthen the stitches during the said reduction in speed in circular knitting and prior to the introduction of said thickening thread, to such an amount that the stitches knitted during the said reduction in speed in circular knitting and without the thickening thread substantially equal in length the normal stitches of circular knitting.

7. In a knitting machine adapted for circular and reciprocatory work, means to operate the parts for circular knitting, means to operate the parts for reciprocatory knitting at less than the maximum speed for circular knitting, means to reduce the speed of the parts for one or more courses just prior to reciprocatory knitting, means to lengthen the stitches during and for reciprocatory knitting, and co-operating connections to 125

lengthen the stitches during and for the reduction in speed just prior to reciprocating knitting.

8. In a circular knitting machine adapted for circular and reciprocating work, means to operate the parts for circular knitting, means to operate the parts for reciprocating knitting at less than the maximum speed for circular knitting, means to reduce the speed of the parts for one or more courses just prior to reciprocating knitting, means to lengthen the stitches during and for reciprocating knitting, and coöperating connections to lengthen the stitches during and for

the reduction in speed just prior to reciprocating knitting to an amount substantially to compensate for the decreased stitch length incident to speed reduction in circular knitting.

In testimony whereof, I have signed my name to this specification, in the presence of two subscribing witnesses.

GEORGE D. MAYO.
